J. F. HARMAN,
OIL BURNER,
APPLICATION FILED MAR. 2, 1920.

1,382,725.

Patented June 28, 1921.

UNITED STATES PATENT OFFICE.

JOHN F. HARMAN, OF KANSAS CITY, KANSAS.

OIL-BURNER.

1,382,725.

Specification of Letters Patent. Patented June 28, 1921.

Application filed March 2, 1920. Serial No. 362,812.

To all whom it may concern:

Be it known that I, JOHN F. HARMAN, a citizen of the United States, and resident of Kansas City, Wyandotte county, State of Kansas, have invented a certain new and useful Improvement in Oil-Burners, of which the following is a complete specification.

The present invention relates to burners, and aims to provide an improved construction of burner of the oil type, and one of the principal objects in view is to devise a burner construction in which the oil vapor is fed into a fuel receiving chamber which is located within the flame zone of the burner, together with provision for preventing overheating of said fuel receiving chamber and of the fuel vapor being fed thereinto.

To this end I have devised a burner construction having a fuel receiving chamber located within the flame zone of the burner and having a vapor generating tube leading through the flame zone and discharging its vapor into the fuel chamber, and a casing or housing arranged to inclose a portion of said vapor generating tube as well as the fuel receiving chamber, said casing or housing providing an air chamber to which air passages lead from the bottom of the burner for conducting a continuous supply of air into the air chamber for cooling purposes.

It is also sought to devise a fuel supply connection having an improved arrangement, in that the conduit for the supply of fuel is arranged to extend for a distance through the flame zone of the burner just prior to its discharge of said fuel into the vapor generating member, for thus effecting an initial heating of the fuel preparatory to the vaporizing action of said generating member.

With these general objects in view, the invention will now be described by reference to the accompanying drawing illustrating one form of construction for embodying the proposed improvements, after which the novel features therein will be particularly set forth and claimed.

In the drawing—

Figure 1 is a side elevation of a burner construction embodying the proposed features of improvement, certain portions of the burner being broken away to disclose the various chambers or compartments of the burner;

Fig. 2 is a plan view of the same with the

casing or housing forming the improved cooling chamber represented in section; and

Figs. 3, 4, and 5 are transverse sections taken on the lines 3—3, 4—4, and 5—5, respectively, of Fig. 1.

Referring now to the said drawing in detail, this illustrates the improved burner structure as comprising a casing or casting 6 of hollow form and providing a fuel or vapor receiving chamber 7 into which the fuel or vapor is discharged from a vapor generating tube 8 provided with a needle regulating valve 9, the ends of said tube being supported in a lug or bracket 10 at the front end of the burner and in the front wall of the fuel receiving chamber 7, as shown in Fig. 1. Air for mixing with the fuel is adapted to be received into said chamber 7 through a passage 12 from a central longitudinal channel or passage 14 in the base of the burner. From the chamber 7 the vapor passes by way of two lateral and downward extensions 15 at the rear of said chamber and at the rear end of the burner, into two vapor distributing chambers 16 extending longitudinally of the casting 6 at the opposite sides of the burner. The said chamber 16 is provided with a plurality of slits or flame orifices 17 along both sides of the burner, and also with a series of similar orifices 18 in the top of the burner to the front of the chamber 7 and underlying the generator tube 8.

The foregoing represents a burner construction of a type commonly in use, in the operation of which it is found that more or less difficulty is experienced from the tendency of the chamber 7 to become overheated and causing the fuel to ignite within said chamber before passing into the distributing chamber. Accordingly I have devised a cooling means for overcoming such overheating tendency due to the position of said receiving chamber within the flame zone of the burner as defined by the flame jets or orifices 17 at the opposite sides of the burner. For this purpose I provide a housing or casing 20 adapted to fit over that portion of the casting 6 which forms the chamber 7 and secured thereto by means of screws 21, the shape and size of said casing such as to form an air chamber 22 surrounding the sides and front end of the chamber 7; as seen in Figs. 1 and 2, the front end of the casing 20 embraces a portion of the rear end of the generator tube 8, for which the front

wall of the casing 20 is provided with an opening 23, and into this front end portion of the chamber 22 air is admitted through a passage 24 communicating with the longitudinal passage 14 at a point slightly in front of the passage 12, the front wall of the chamber 7 forming the vertical partition between the passages 12 and 24. Additional passages are provided for admitting air to the sides of chamber 22, as indicated at 25 in Figs. 1, 2, and 4, the passages being formed by providing partitions 26 between the side walls of the longitudinal channel 14 and the two distributing chambers 16, the 15 said passages 25 being thus arranged to receive air from the bottom face of the burner and conduct the same up through the burner casting 6 into the bottom of the chamber 22. The fuel supply to the burner is conducted thereto by means of a pipe 28 leading to the outer end of the vapor generating tube 8. However, for effecting an initial heating of fuel liquid prior to its entry into the tube 8, I extend this pipe 28 through the 25 flame zone provided at the front end of the burner over the orifices 18, Figs. 1 and 3 of the drawing showing said pipe extended parallel to the tube 8 into proximity to the front end of the casing 20 and then back to the outer end of the tube 8 through the flame zone of the burner and on the opposite side of said tube 8.

It will thus be seen that I have provided a simple and efficient form and arrangement 35 of burner construction for carrying out the desired objects of the invention. By the means of my improved cooling structure the temperature of the fuel or vapor receiving chamber 7 is kept below the danger point at 40 which the vapor within said chamber would ignite, and said fuel vapor still maintained at a sufficiently high temperature for efficient combustion on being conducted through the passages 15 and distributed 45 thereby into the chambers 16 to the flame orifices 17 and 18. For allowing the proper circulation of the air through the chamber

22, the latter, it will be noticed, is provided with a plurality of vent openings 30. (See Figs. 1 and 4.) By the arrangement shown 50 and described with reference to the oil of fuel pipe for conducting the fuel to the generator 8, and extending this pipe through the flame zone of the burner, it is evident that an initial heating action is imparted to 55 the fuel prior to its entering the generator tube 8, with the result that said fuel is supplied in a pre-heated condition, in which state a much more effective vaporizing action by the generator tube 8 is made possible. 60

While I have shown and described what I now regard as the preferred form of construction, I desire to reserve the right to make such changes as may fairly fall within 65 the scope of the following claims.

What I claim is:

1. An oil burner comprising a casing providing a fuel receiving chamber and having flame orifices arranged to provide a flame zone surrounding said chamber, a vapor generating tube passing through said flame zone and feeding into said chamber, and a second casing interposed between said orifices and said chamber and surrounding a 75 portion of the generating tube adjacent to said chamber for providing an air chamber adapted to prevent overheating of the vapor being fed into said fuel receiving chamber. 80

2. An oil burner comprising a casing providing a fuel receiving chamber and having flame orifices arranged to provide a flame zone surrounding said chamber, and a second casing interposed between said orifices and said fuel receiving chamber and providing an air chamber surrounding said fuel receiving chamber for preventing overheating thereof, said first casing being provided with passages for conducting air from the lower face thereof into the bottom of said 90 air chamber.

In witness whereof I hereto affix my signature.

JOHN F. HARMAN.
